US0D1042693S

(12) United States Design Patent (10) Patent No.: US D1,042,693 S
(45) Date of Patent:  Sep. 17, 2024

(54) PUTTER HEAD

(71) Applicant: Topgolf Callaway Brands Corp.,
Carlsbad, CA (US)

(72) Inventors: Jack Glorioso, Carlsbad, CA (US);
Luke Williams, Carlsbad, CA (US);
Patrick Dawson, Poway, CA (US);
Sean Toulon, Vista, CA (US); Taro Monuki, Tokyo (JP); Terakado Hiroki,
Tokyo (JP)

(73) Assignee: Topgolf Callaway Brands Corp.,
Carlsbad, CA (US)

() Term: 15 Years

(21) Appl. No.: 29/881,695

(22) Filed: Jan. 5, 2023

(51) LOC (14) Cl. 21-02

(52) U.S. Cl.
USPC D21/743

(57) CLAIM

The ornamental design for a putter head, as shown and described.

DESCRIPTION

FIG. 1 is a front elevation view of a putter head;
FIG. 2 is a rear elevation view thereof;
FIG. 3 is a top plan view thereof;
FIG. 4 is a bottom plan view thereof;
FIG. 5 is a heel-side elevation view thereof;
FIG. 6 is a toe-side elevation view thereof; and,
FIG. 7 is a top perspective view thereof.
The broken lines shown in the drawings form no part of the claimed design.
